CLAIM

The ornamental design for a ski, substantially as shown and described.

DESCRIPTION

FIG. 1 is a bottom plan view of a ski showing my new design;

FIG. 2 is a fragmentary view of the design of FIG. 1 showing the upper portions of the ornamental design thereof on an enlarged scale;

FIG. 3 is a side elevational view of the design of FIG. 1, the side opposite being substantially a mirror image; FIG. 4 is a top plan view thereof.

The characteristic feature of my design resides in the graphic ornamentation best shown in FIGS. 1 and 2.
